ABRASIVE BLOCK

George Bafin, Los Angeles, Calif.

Application December 14, 1942, Serial No. 468,945

1 Claim. (Cl. 51—185)

My invention relates to mounts or holders for an abrasive material such as sandpaper, emery cloth and the like, and has among its objects and advantages the provision of an improved block structure designed to constitute a measuring instrument for cutting such material to proper lengths from a supply roll to fit the block structure in a snug manner, wherein the construction is such as to facilitate placement and removal of the abrasive and to effectively hold the material in an efficient manner, in addition to embodying a structural contour such as to provide a maximum sanding surface with a minimum of abrasive waste.

In the accompanying drawing:

Figure 1 is an end view illustrating the block sections in an open position;

Figure 2 is an end view illustrating the block sections in their closed positions for work purposes;

Figure 3 is a face view of the block sections in the position of Figure 1;

Figure 4 is a sectional view taken along the line 4—4 of Figure 3; and

Figure 5 is a top plan view of the block sections in the position of Figure 1.

In the embodiment selected for illustration, I make use of block sections 10 and 12, which are identical with respect to size and contour. These block sections are swingably and pivotally connected one with the other through the medium of links 14 and screws 16 threaded into the respective block sections 10 and 12 at the medial planes thereof. The links 14 are of such lengths and the screws 16 so positioned that the block section 12 may be completely reversed to position either face in overlapping engagement with the block section 10. Figure 2 illustrates the normal working relationship of the two block sections. Each of the block sections is provided with a groove 18 which is arranged at an acute angle to an parallels the edge face 20 of its respective block section. Both grooves 18 are spaced the same distances from the respective edge faces 20.

Figures 1 and 2 illustrate a sandpaper strip 22 as having edge margins 24 lying in the grooves 18. When the block sections are moved to the position of Figure 2, the strip 22 is pinched firmly between the block sections by reason of its engagement with the pressure faces 26 on the block sections. To connect the block sections 10 and 12 in a sturdy manner for work purposes, the section 12 is provided with pins 28 receivable in sockets or bores 30 in the section 10. Thus the two block sections are keyed firmly against

relative movement when the block is being manipulated for work-finishing purposes.

Considerable difficulty has heretofore been encountered in cutting sandpaper and emery cloth to proper lengths from a rolled supply. To facilitate manipulation of the sandpaper block in connection with finishing work, it is highly desirable to connect the abrasive material in a firm manner with the block. The abrasive material should fit snugly so as to eliminate slack. In the instant case, the abrasive material may be cut to exact lengths through the medium of the block as a measuring instrument.

When cutting a length, the end of the strip 15 is inserted in the grooves 18 in the block section 10 and block sections 10 and 12 are then closed to position of Figure 2. The strip is then wrapped about the block section 10 and the block section 12 and across the two faces 20 and severed along the line 32. The depths of the grooves 18 and 20 the widths of the faces 26 are such that when the loose end of the abrasive material is folded inwardly across the face 26 on the block section 12 and the end inserted in the groove 18 in this block section, the material is of such length as to be drawn tightly to all the exterior faces of the block when the sections are closed to the position of Figure 2.

After cutting the abrasive material for length, 30 the block section 12 is pivoted away from the block section 10 to permit the latter section to be grasped in the left hand, with the thumb of that hand pressed over the sheet extending across the face 26 of that section. The section 12 is 35 then completely reversed to press against the sheet lying on the face 26 of the section 10 and the thumb of the left hand is then placed over the section 12 to support the block assembly. With the block section 12 completely reversed, 40 the groove 18 in the block section 12 is readily accessible for insertion of the other end of the sheet. This end of the sheet is then held against the face of the block 12 and the latter is completely reversed and dropped to the position of 45 Figure 2, which draws the sheet tightly to the contour of the block assembly and clamps the two end margins firmly between the two block sections.

The block sections 10 and 12 in combination 50 with the faces 26 and the grooves 18 constitute a measuring instrument through the medium of which the pieces may be cut to exact lengths to fit the block structure in a taut manner. This facilitates cutting of the lengths and eliminates

waste incident to cutting of the lengths in excessive and insufficient amounts.

Without further elaboration, the foregoing will so fully illustrate my invention, that others may, by applying current knowledge, readily adapt the same for use under various conditions of service.

I claim:

An abrasive holder comprising a block formed of first and second sections, a pair of links pivotally and swingingly connecting said sections, each link having one end pivotally connected to and centrally of an end edge of one section and its other end similarly connected to the like edge adjacent to one of its longitudinal edges, 15

said sections normally lying face to face and having grooves extending longitudinally in these opposed faces to receive the end margins of a sheet of abrasive material trained over and about the outer side, top and bottom faces thereof, the groove in one of said sections being oppositely angled with respect to the groove in the other of the sections, and a pair of pins projecting from the inner face of one of said sections for engagement with sockets formed in the opposed face of the other of the sections, the opposite inturned end portions of the abrasive sheet being firmly clamped between the sections when the latter are normally disposed.

GEORGE BAFIN.
